UNITED STATES PATENT OFFICE.

WILLIAM C. O'BRIEN, OF BALTIMORE, MARYLAND, ASSIGNOR, BY DIRECT AND MESNE ASSIGNMENTS, TO CLINE ELECTRIC MANUFACTURING COMPANY, OF CHICAGO, ILLINOIS, A CORPORATION OF ILLINOIS.

STARTER FOR ELECTRIC MOTORS.

Application filed November 4, 1924. Serial No. 747,751.

This invention relates to distant controlled motor starters. The starter of my invention comprises a normally open main contactor, for opening and closing the armature circuit of the motor, a magnet for moving said contactor to closed position, and a manually controlled switch for opening and closing the circuit to said magnet, in combination with one or more normally open auxiliary contactors, each adapted, when closed, to cut out a section of the starting resistance, means whereby said main contactor applies tension to the auxiliary contactors tending to close the latter, after the main contactor has closed the armature circuit, and means controlled by the current in the armature circuit for preventing said auxiliary contactors from closing while the current in the armature circuit is above a predetermined quantity.

More specifically, the invention comprises a main contactor which is normally held in open position by gravity and which is provided with a yielding contact member adapted to permit the body of the contactor to move after the armature circuit has been closed, one or more auxiliary contactors, also normally held in open positions by gravity, magnets in the armature circuit for preventing the closure of said auxiliary contactors immediately upon the closure of the armature circuit, and springs for closing said latter contactors, said main contactor adapted to apply tension to said springs, after said main contactor has closed the armature circuit. With this arrangement, a single magnet serves to close the main contactor and also to store energy in each of the auxiliary contactors, for closing the latter as soon as released by their respective magnets.

In the accompanying drawing,

Fig. 1 is a front elevation of the starter;

Fig. 2 is a side elevation of the same, looking from left to right in Fig. 1;

Fig. 3 is a similar side elevation, one of the auxiliary contactors being removed;

Fig. 4 is a diagrammatic view showing the arrangement of the circuits; and

Fig. 5 is a side elevation of one of the auxiliary contactors.

Referring to Fig. 1 of the drawing, *a* represents a suitable panel or base plate of insulating material upon which the starter is

mounted. The starter comprises a main contactor *b* and one or more auxiliary contactors, two of these, indicated at *c* and *c'*, being shown in the drawing. The main contactor comprises a metal plate 1, partly or wholly of iron, having overturned ears 2 near one end, and a pivot pin 3 extends through these ears and through an iron bracket 4, which latter is secured to the base *a*. Upon this bracket 4 is a pole piece 5, which projects toward the pivoted plate or armature 1 and a magnet coil 6 surrounds this pole piece. When the magnet is energized, the plate or armature 1 rocks toward the pole piece, as indicated in dotted lines in Fig. 2, and when the magnet is de-energized, the plate rocks away from the pole piece, as shown in full lines in said figure. A metal strip 7, preferably of non-magnetic material, such as copper, is secured to the plate or armature 1 by screws 8, and this strip projects upwardly beyond the coil 6 and is thence bent inwardly toward the base plate as shown at 7^a, and a contact piece 7^b is connected to the part 7^a by a pivot pin 7^c. This contact piece is normally pressed toward the base of the starter by a spring 9 which is arranged between the contact piece 7^b and an arm or bracket 10 on the part 7^a. This spring surrounds a pin 11, which extends loosely through the bracket 10 and the contact piece 7^b, and this pin is headed so as to form a stop for the part 7^b and limit its movement away from the bracket 10. With the arrangement described, when the armature 1 is attracted by the magnet 6, the contact member 7^b will first engage a stationary contact 12 and the continued movement of the armature will cause the contact member 7^b to rock about its pivotal point and compress the spring 9, as shown in dotted lines in Fig. 2. When the current is cut off from the magnet, the armature will rock about the pivot pin 3, the expansion of the spring 9 tending to quicken this movement, and an arm 7^d at the lower end of the strip 7 will engage the bracket 4 and limit the outward rocking movement of the armature. The armature 1 of the main contactor has laterally projecting arms 1^a and 1^b, which extend in front of the auxiliary contactors *c* and *c'*, respectively. These latter contactors are alike in construction, each comprising a rocker 12, pivoted between its ends on a pivot

pin 13 in a bracket 14 mounted on the base. These rockers are preferably of copper, or other non-magnetic material. The rocker *c* has at its upper end a contact 15, adapted to engage a stationary contact 16, and the rocker *c'* has at its upper end a contact 17, adapted to engage a stationary contact 18. The lower end of the arm 12 of the contactor *c* extends over the pole of a magnet 19, arranged in the armature circuit of the motor, and the lower arm of the contactor *c'* extends over the pole of a magnet 20, also arranged in the armature circuit of the motor. These rockers carry adjustable iron bolts 25, which constitute armatures for the magnets 19 and 20. On the lower part of the rocker 12 is secured a flat spring 21 which projects upwardly in front of the body of the rocker, and the free end of this spring extends beneath a stop 22, formed by an arm which projects outwardly from the body of the rocker near its contact end, as shown. A similar spring, 21^a, and a stop 22^a are shown upon the contactor *c'*.

Upon the arms 1^a and 1^b of the main contactor are arranged pins 23 and 24 which are adapted to bear upon the flat springs 21 and 21^a, respectively, after the contact member 7^b of the main contactor has engaged the stationary contact 12 and closed the armature circuit. It is important that these pins shall not engage the springs until after the armature circuit has been closed. The closure of the armature circuit causes the magnets 19 and 20 to become energized, as will be further explained, and these magnets hold the auxiliary contactors in open positions as long as the armature current is above a predetermined quantity. After the circuit has been closed, the pins 23 and 24, which move with the main contactor, bear on the springs 21 and 21^a and press the latter to the dotted line position shown in Fig. 2, thus storing energy in the springs, and as the magnets 19 and 20 of the auxiliary contactors weaken, during the acceleration of the motor, these release said contactors in succession and the contactors are immediately moved to their closed positions by the tension of the springs. When the magnet of the main contactor is de-energized, the latter moves to the open position and thus the pins on said contactor are moved out of engagement with the springs on the auxiliary contactors and the latter move to open positions by gravity.

Referring to the diagram Fig. 4, L and L' indicate the supply wires of an electric circuit and *m* indicates a direct current electric motor comprising the armature 26 and field winding 27. Current from the supply wire L extends through conductor 28 to the coils of a suitable blow-out magnet 29, the poles of which are arranged adjacent the stationary contact 12, and from the coil of the blow-out magnet the circuit proceeds by conductor 30 to said contact. From the contact 12, a circuit for the magnet of the main contactor extends through conductor 31 to the coil 6 of said magnet, thence through conductor 32 to a manually operable switch 33, thence through conductor 34 to the side L' of the supply circuit. By closing the switch 33, it will be evident that the magnet 6 will move the main contactor to the closed position and this will bring the member 7^b of said contactor into engagement with the stationary contact 12. The field winding 27 of the motor is connected by conductor 35 to the contactor *b* and when the latter is in closed position, current will flow from the contact 12 through said contactor to the field 27, thence by conductor 36 to the supply wire L'. The main contactor is electrically connected to the auxiliary contactor *c* by conductor 37, and to the auxiliary contactor *c'* by conductor 38. When the main contactor is first closed, the current to the armature of the motor extends from the supply wire L through the blow-out magnet and contact 12 to the main contactor *b*, thence through conductor 37 to the auxiliary contactor *c*, which is held in open position by the magnet 19, thence through conductor 39 and resistance section 40 to the coil of magnet 19, thence through conductor 41 to the coil of magnet 20, thence through resistance 42 and conductor 43 to conductor 44, thence through the armature of the motor to the supply wire L'. As the magnets 19 and 20 will be energized the moment the flexible contact member 7^b touches the contact 12, these magnets will hold the auxiliary contactors in open position. Immediately after the closure of the armature circuit, the final movement of the main contactor will cause pressure to be applied to the springs on the auxiliary contactors, tending to close the latter. As the motor accelerates, the current in the armature circuit will decrease and when the volume of this current has fallen to a predetermined quantity, the magnet 19 will be so weakened that the tension applied to the spring 21 will cause the contactor *c* to rock away from said magnet and said contactor will engage the stationary contact 16. When this occurs, the auxiliary contactor *c* will short circuit the resistance section 40, the coil of magnet 19 and a part of the coil of magnet 20 through a circuit which extends from the side L of the supply circuit, through the coil of the blow-out magnet and the main contactor and conductor 37 to the auxiliary contactor *c* and contact 16, thence through conductor 45 to an intermediate part of the coil 20, thence through a part of said coil and the resistance 42 and conductors 43 and 44 to the armature and thence to the side L' of the supply circuit. Upon the cutting out of section 40 of the resistance and the magnet windings, the current in the

armature circuit will increase and then decrease as the motor accelerates further, and when the current then falls to a predetermined amount the magnet 20 will be weakened sufficiently to release the auxiliary contactor c' and the spring 21^a will then immediately cause the said contactor to rock to closed position. When this contactor closes, the remaining section of the coil 20 and 5 the resistance section 42 will be short-circuited, the current then flowing directly from the main contactor through conductor 38 to the auxiliary contactor c' , thence to contact 17 and through conductors 45 and 44 to the armature. The 10 motor will then run with all of the resistance cut out. When it is desired to stop the motor, it is only necessary to open the switch 33 and this will cause the magnet of the 15 main contactor to be de-energized and the pressure of the main contactor against the springs of the auxiliary contactors will then be released and the several contactors will rock by gravity to their open positions, 20 ready for the next starting operation.

What I claim is:

1. In a starter for electric motors, the combination of normally open, main and auxiliary contactors, a normally inoperative 30 spring for closing said auxiliary contactor, a magnet for opposing said spring, and parts mounted on said main contactor for successively closing the circuit of said magnet and placing said spring in operative condition, 35 substantially as described.

2. In a starter for electric motors, the combination of normally open, main and auxiliary, pivoted contactors, a normally inoperative leaf spring mounted on said pivoted auxiliary contactor for closing the latter and a magnet for opposing the operation of said spring, said main contactor having a yielding contact and a rigid abutment arranged to successively close the circuit of 40 said magnet and engage and tension said leaf spring, substantially as described.

3. A starter for electric motors comprising a normally open main contactor adapted to close and open the armature circuit, a 45 magnet for moving said contactor to closed position, a switch controlling the circuit of said magnet, a normally open auxiliary con-

tactor, a magnet in the armature circuit of the motor adapted to prevent the closure of the latter contactor after the armature circuit has been closed and until the starting current falls to a predetermined value, and a spring carried by the auxiliary contactor, said main contactor, after it has closed the armature circuit, being adapted to engage said spring and apply tension to the same tending to close the auxiliary contactor. 55

4. A starter for electric motors comprising a pivotally supported main contactor, 60 normally in open position and adapted to close the armature circuit, a magnet for moving said contactor to closed position, a switch controlling the circuit of said magnet, an auxiliary contactor pivotally supported adjacent the main contactor and normally in open position, a magnet in the armature circuit for holding the auxiliary contactor in open position until the starting current falls to a predetermined value, and 65 a spring carried by the auxiliary contactor, said main contactor, after it has closed the armature circuit, being adapted to engage said spring and apply tension to the same tending to close the auxiliary contactor. 70

5. A starter for electric motors comprising a pivotally supported main contactor having a yieldingly mounted contact member, a stationary contact opposed to said member, said contactor being normally in open position 75 and adapted to close the armature circuit when said member engages said contact, a magnet for moving said contactor to closed position, a switch controlling the circuit of said magnet, an auxiliary contactor pivotally supported adjacent the main contactor and normally in open position, a magnet in the armature circuit for holding the auxiliary contactor in open position until the starting current falls to a predetermined value, and 80 means operable by the main contactor in moving to its closed position, after said contact member has engaged said stationary contact, for applying tension to the auxiliary contactor tending to close the same. 85

In testimony whereof I hereunto affix my signature.

WILLIAM C. O'BRIEN.
